(57) **CLAIM**

The ornamental design for a communications headset, as shown and described.

DESCRIPTION

FIG. 1 is front-top-left perspective view of a communications headset showing our new design;

FIG. 2 is a back view thereof;

FIG. 3 is a top view thereof;

FIG. 4 is a left side view thereof, the right side view is a mirror image;

FIG. 5 is a bottom view thereof; and,

FIG. 6 is a front view thereof.

The broken line showing of the unclaimed environment forms no part of the claimed design.
